Patrick J. Clifford,

UNITED STATES PATENT OFFICE.

PATRICK J. CLIFFORD, OF FALLS, PENNSYLVANIA, ASSIGNOR TO THE CLIFFORD AUTOMATIC TRAIN STOP COMPANY, OF SCRANTON, PENNSYLVANIA, A CORPORATION OF DELAWARE.

AUTOMATIC TRAIN-CONTROL APPARATUS.

Application filed January 5, 1923, Serial No. 610,879. Renewed August 17, 1927.

The invention in part concerns means whereby the operations of an automatic train control system of the general character herein disclosed can be carried out without interfering with the normal operation of the block signalling with which the road is equipped.

The automatic train control system as hereinafter described employs a primary relay on the vehicle which controls the operation of the apparatus on the vehicle and is itself controlled by the electrical conditions in the trackway rail or rails traversed by the vehicle. This primary relay derives its current from the trackway rail or rails in circuit with a suitable source of current in each block, and it is in connection with an added system of this general character that the present invention is to cooperate to prevent the standard block or other signalling system from being interfered with and giving false indications.

The invention includes, however, other features, as will be hereinafter described, and particularly pointed out in the claims, which can be used with or without association with a block signalling system.

In the accompanying drawings:

Figure 1 is a diagram of a single track road with a vehicle thereon and with the primary relay connected up on one side of the vehicle or train members, such as the engine and tender. This view shows features of the invention without connection or association with the signalling system.

Fig. 2 is a diagram of the vehicle on the rails of a single track road with the primary relay connected up to be controlled by the electrical condition in one of the rails, and illustrating the system but showing only the track battery and a track relay representative of the signalling system.

Fig. 3 is a diagram showing the means whereby interference with the signalling system is prevented.

Fig. 4 is a diagram of the system in more complete form.

Fig. 5 is a diagrammatic view of the apparatus on the vehicle.

Fig. 5^a shows an example of a speed governed means for controlling certain circuits.

Fig. 6 is a diagram of the blocks of the railway.

Figs. 7 and 8 are diagrammatic views of modified forms of primary relay connections, which, like Fig. 1, however, cause the relay to be controlled by the drop in potential between points on the track system, for in turn controlling apparatus on the vehicle.

Fig. 9 is a view, diagrammatically, of another form of primary relay affected by the drop in potential but adapted to be unaffected by shocks or jars.

Fig. 10 shows the primary relay more in detail.

In Figs. 1 and 2 the numerals 1 and 2 are the trackway rails of a single road, the division between the blocks being indicated by the cross lines.

The primary relay PR is connected up with axles of the vehicle on one side thereof or of the engine and tender, it being understood that the axles represented may be either those of the locomotive, or one may be of the locomotive and one of the tender. The direction of traffic is in the direction of the arrow. The primary relay is of a sensitive character connected up in a wire of low resistance so that the drop in potential between the points 5 and 6 will be measured by the relay which in doing so will be operated so as to control the functions of the apparatus on the vehicle whether this be automatic train stop mechanism or a signalling system, or both.

Current is supplied to the rail 1 from a battery NP, from the negative side of which a wire 7 extends to the rail 1 at point 3, the return wire 8 leading back to the positive side of the battery from point 4 on the rail 1.

This single wire system will operate entirely satisfactorily on a road not equipped with a signalling system, but when associated with a signalling system means are sometimes found necessary to be provided for preventing interference with the operation of the said signal system.

In Fig. 2 parts of a signalling system are shown in connection with the system shown in Fig. 1, and this illustrates the conditions under which interference with the working of the signal system will take place.

In this diagram, Fig. 2, considering only the circuit from battery NP through 7, 3, 1, 5, 6, 4, 8, and back to P, this circuit is absolutely operative so far as receiving the in-

dition through the galvanometer PR is concerned. When, however, the signal system is considered, interference with the latter is found to exist.

5 Between 3 and 5 there is a certain drop of potential—this drop is identical through all possible paths. In addition to the direct path, there is a path from 3, through relay T, of the signal system, through rail 2, across 10 the car axle to 5. The division of the current through these two paths is determined by their relative resistances. In long blocks these relative values may be such that a sufficient current will flow through signal relay 15 T and energize it, thus causing a "false clear" indication on the signals.

If, however, the drop of potential between the rails can be eliminated, no current will unduly flow through signal relay T. 20 This is the purpose of the wiring in Fig. 3. By impressing equal voltages on each of the rails, 1 and 2, with current flowing in the same direction through both of them, there is a negligible difference of potential between 25 points 3 and 9, hence no current is flowing here and signal relay T remains de-energized when shunted by the train—hence the signal system is unaffected and entirely normal in its operation, and hence a false proceed or clear indication will be prevented.

This balancing system of Fig. 3 includes the wire sections 11 and 12, connected respectively to the rail 2 at 9 and 10 at the ends of the block, like the wires 7 and 8, and 30 having therein the battery NP¹, the negative side being connected with wire 11 and the positive side with wire 12. The rest of the system is as shown diagrammatically in Fig. 2, wherein, like in Fig. 1, the wires 7 and 8 are connected at the ends of the block to the rail.

In the case with the train in the position indicated in Fig. 3, drop of voltage from 3 to 5 in rail 1 and from point 13 to 9 of rail 45 2 is substantially the same.

With this system the current through the relay PR is not affected by the length of the train or by the presence of another train in the same block. The imposed current does 50 not interfere in any way with the roadside signals, and the indications of the primary relay or galvanometer PR are rendered steady, accurate, and reliable.

Referring to Fig. 4, which shows a development of the system above outlined, it will be understood that the elements shown in light dotted lines are parts of the ordinary roadside signalling system.

The present system is capable of use with 60 the automatic train stop apparatus disclosed in an application for Letters Patent of the United States, filed April 17, 1922, Serial No. 553,429, of P. J. Clifford. In that application the method of securing the 65 indication, like the method above outlined,

consists in using a sensitive galvanometer to measure the voltage drop between points on the trackway.

This indication may be obtained, however, in a variety of ways, viz: (1) The galvanometer may be placed in a connection so as to be affected by the drop diagonally across the locomotive or locomotive and tender, and this may be referred to as the "double rail" circuit because the circuit is from one rail 75 through the wheel on one side diagonally to the wheel on the other rail and in this diagonal connection the galvanometer is located; (2) the measurement of the drop in voltage may be along one side of the locomotive or vehicle or locomotive and tender, as in Fig. 1 above referred to, and this requires the "single rail circuit"; or (3) the measurement of the drop may be in respect to both sides of the said locomotive in parallel, and this system may be referred to as the "double single rail circuit". Figs. 3 and 4 show the circuit for uni-directional traffic.

An essential feature of the plan illustrated in Figs. 3 and 4 is the impression of two equal and independent electrical potentials upon two trackway rails; in one direction to secure a "proceed" indication or condition; in the other direction to secure a caution indication. The absence of this potential produces the stop indication or condition of the apparatus. Because the potentials above referred to are equal and independent, the system will not interfere with the track circuits and no special protective devices will be required to make the signal system function properly. Therefore, though dependent on the track circuit for its operation, and though both the trackway and imposed circuits use the same rails, the imposed current cannot affect the signal track relay or the proper operation of the signal system.

In carrying out one part of the present invention, only two relays are required in each block, though it will be understood that so far as the ordinary or standard signalling system is concerned, relays belonging peculiarly to it will be employed as usual. The two relays which function in connection with the present system particularly are those marked T and B with proper exponents indicating the respective blocks, see Fig. 4. Those marked T¹, T², T³, T⁴ and T⁵ are the ordinary track relays, such as are employed in existing signalling systems, there being combined therewith, however, additional contacts for carrying out the purposes of the present invention. Those marked B¹ to B⁵ are high resistance relays for changing the polarity of the circuits in order to secure an advance signal indication. Two independent batteries are installed in each block, in addition to the ordinary track batteries, in order to impress independent 125

potentials upon the trackway rails, one battery supplying one rail and the other supplying the other rail. The usual track batteries are marked TB with exponents denoting the block to which they belong and the two additional independent batteries for each block peculiar to this invention are marked in Roman numerals I, I' to V, V', as shown in Fig. 4. The complete independence of the sources of the two imposed currents such, as an example, as the batteries I, I', and the circuits in which they are located is desirable in order to prevent a shunt of the track circuit, and therefore two independent line wires are employed in the system, for instance, as at 101, 121, this being true of each block; and under certain conditions a third wire is used for the control of the relay B¹, etc., in each block, this wire being marked 153 in the block being considered, though this connection may be altered.

Considering the normal operation of the circuits with the train moving through block #3, in the arrow direction Fig. 4, no other train being present: The track relay T³, energized in the ordinary manner from the track battery TB³, will be shunted by the presence of the train denoted by X, and its contacts will drop, including those contacts added by the present invention. The imposed circuits, therefore, will be closed and may be traced as follow: Starting from battery IV the current flows through front contact on relay B⁴, to wire 307, front contact of track relay T⁴, which remains energized (because no train is present in block #4 to shunt it), wires 306, 305, trackway rail 304, wire 303, back contact of track relay T³, wires 302, 301, front contact of relay B⁴ and back to battery IV. The passage of the current through rail 304 contributes one-half of the condition necessary to the "proceed" indication, or condition on the vehicle, by the operation of the sensitive galvanometer which responds to the drop in potential along the trackway rail as above described; in connection with the diagrams 1 to 3.

From the second added battery IV' a circuit will be established through front contact of relay B⁴, wire 327, front contact of track relay T⁴, wire 325, trackway rail 324, wires 323, back contact of track relay T³, wire 321, front contact of relay B⁴, back to battery IV'. The passage of current through rail 324 contributes the other half of the condition necessary to the "proceed" indication or condition on the vehicle.

It is to be understood that this condition of each rail's supplying one-half of the necessary indication is true only when the locomotive is supplied with two parallel galvanometer circuits, each connected along its own side of the locomotive. In the event that the locomotive is equipped with one gal-

vanometer; the energy in one rail will be sufficient to give the necessary indication. In this latter case the other rail circuit is used for the protection of the existing signal system by balancing the electric potential at the two sides of the track signal relays.

It will be seen that both imposed circuits are normally open until a train enters the block, being made by the back contacts on the track relay for that block. Hence at this time all other imposed circuits in the other blocks are normally open and no current is flowing. Certain of the relays B¹, B², etc., are energized, however, a small current flowing through their high resistance windings. Considering, for instance, the relay B³, the current would go by the path from battery, front or back contact of the preceding or advance relay B⁴ in this case, wires 301—352—353—306, front contacts on preceding or advance track relay T⁴, wires 307, front or back contact on preceding relay B⁴ and back to battery.

Stop indication.—This indication is obtained in the block #2 behind the train by definitely opening the imposed circuits of said block #2 by means of the break at front contacts on track relay T³, and this condition is illustrated in Fig. 4, where the contacts of T³ have dropped consequent upon the presence of the train in block #3. Under this condition there will be no current in rails 224, 204 of this block #2, the circuits of both batteries III, III' being open, and hence there will be no potential drop that can be measured by, or that will affect, the sensitive primary relay or galvanometer PR of a train coming into block #2.

Hence no matter if a train enters block #2 and causes contacts of relay T² to drop the imposing circuits of rails 204, 224 will remain open and a stop indication or condition to this following train in block #2 will result.

By the same means, i. e., the dropping of contacts of track relay T³ consequent upon the presence of a vehicle in block #3, the energizing circuit of relay B² of the following block #2 will remain open, causing its contacts to drop and thus changing the polarity of the circuits in block #1, so that a vehicle, entering that block and causing the contacts of its track relay T¹ to drop and thus making the imposed circuits through its back contacts from batteries II and II' through rails 124 and 104, notwithstanding these actions, will receive an advance caution indication, or bring about a caution condition of the apparatus on the vehicle.

It is to be understood in this connection that the sensitive galvanometer PR on the vehicle is a polarized relay. The relay B' of block #1, though energized by a current of reversed polarity, is a neutral relay, and

hence picked up, causing the block in rear of block #1 to be in readiness to give a normal "proceed" indication or condition of the apparatus on the vehicle.

5 Now considering the conditions ensuing when the front wheels of the vehicle have entered block #4; track relay T^4 is now shunted and its contacts drop, closing the circuits for imposing current on the rails of 10 block #4, and supplying the necessary "proceed" indication or condition to the locomotive as it enters this block. At the same time the imposed circuits of block #3 are opened through the front contacts of relay 15 T^3 . Relay T^3 is still shunted by the back wheels of the vehicle or train, so that blocks #2 and #1 remain unchanged. Hence at this time block #1 still indicates advance caution and block #2 indicates stop, block 20 #3 indicates stop, and block #4 indicates proceed. If the train now passes entirely into block #4 the relative condition of blocks still obtains, but in respect to one block in advance of these which we have 25 been considering above. Relay T^3 is no longer shunted and has picked up and hence block #1 now indicates proceed, block #2 caution, block #3 stop, and block #4 proceed.

30 Where in the claims the term "train control apparatus" is referred to, this is to be construed in a generic sense to mean that automatic train stop apparatus on the train will be controlled by the present invention, 35 or that suitable signals on the vehicle will be operated to indicate to the engineer that he is to take action or not, as the case may be, in manually exerting control of the running of the train, or both train stop and signals may be used.

40 While two batteries, as for instance I , I' , etc., have been shown herein for impressing electrical potential on the trackway rails, as above described, for controlling the primary relay on the locomotive, it will be understood that this electrical potential may be secured from sources other than these two batteries, which are shown herein as additions to each block.

45 For instance, the function of one of these batteries may be performed by a battery which will perform a function in connection with the signalling system and take the place of the battery used ordinarily for that purpose, as the signal operating battery.

The track relays T^1 , T^2 , etc., may be the ordinary 2 ohm or 4 ohm relays of the usual signal system.

50 It will be observed that the invention is shown in connection with an end fed signalling system in which the track batteries TB , TB^1 , etc., are connected with the ends of the blocks, but the invention is not limited in this respect.

55 The present apparatus, like that of the

application referred to, is of the continuous control type, using a method of conduction as the principle of its operation. It has nothing extending out or suspended downward from the vehicle, thereby eliminating 70 the use of ramps, sliding shoes, and track magnets for induction purposes.

Continuous control is obtained whereby the engineer does not depend upon indications received at fixed wayside signal locations, but is immediately advised of the condition, or a change therein, two blocks ahead of his train. If he fails to act according to the automatic indication received, the device automatically operates to protect the 80 train by stopping it.

The device is electro-pneumatic and is operated by two electric and one air circuit, namely:

The track circuit.

The locomotive circuit.

The air circuit.

The electric track circuit is the means by which current is provided whereby the sensitive relay PR of the locomotive apparatus is 90 energized on a clear block.

The electric circuit on the locomotive is the means by which a system of continuous signal indications are provided; this circuit also keeps an electro-magnet energized to 95 hold the air brake in "normal" or off position. All circuits are designed to operate without interfering with the manual operation of any existing air-brake system.

All circuits are designed on the closed 100 circuit principle; any defect in the circuits will result in an automatic brake application.

This train control unites the signal system and the air brake, making one perfect 105 unit of both, and does not interfere with the proper operation of either one, but is so synchronized that it immediately reflects in the braking system any change in track conditions, such as an open switch, an open drawbridge, a broken rail, or a dangerous fouling point condition that would cause a "side-swipe" or a backing up movement against the current of traffic.

The attached drawings are for the purpose of illustrating the principles of operation in a "clear block," an "advanced signal block," a "caution block," and an "occupied block."

In Fig. 5 all contacts are shown in the position they would assume on a "clear" block. The polarized relay PR is shown in a connection extending diagonally of the vehicle, or in the particular illustration herein included, between the front journal box of the locomotive and the rear journal box of the tender, though this connection may extend as in Fig. 1 on one side of the vehicle, or as in Figs. 7 to 9. Besides the primary relay PR there are relays similar to those 120

of the said Clifford application, as follows: A slow acting relay SAR, a signal relay S, and a time limit relay TL, and in addition there is used a light AYS serving as the advance yellow signal, a relay AR controlling an advance red signal ARS, and a relay GOV. The contacts of the polarized primary relay are shown at 15, 16 and the armature at 17.

When the vehicle is in a clear block, the direction of current flow in the polarized relay PR is such that armature 17 will make contact at 16. The path of the current will then be: from negative side of the 6-8 volt battery VB, armature 17, contact 16, coil of slow acting relay SAR, and to positive side of the battery.

Fig. 6 is a diagram showing where the changes in signal indications take place. While the train is in the "clear" block O the green light G, Fig. 5, will be displayed. As soon as the front wheels pass the insulated joints into the "advance signal" block #1, the engineer will receive a yellow signal AYS advising him that he is approaching a caution indication. The green light will remain displayed and advises him of the condition of the signal just passed, thus providing an absolute check upon the condition of the signalling system.

If the engineer has governed his train according to the advance caution indication received, and has brought his train down within control speed, he may pass the caution board. As soon as he passes the insulated joints at beginning of the caution block #2; both lights, advance yellow AYS and clear (green G), will disappear and a yellow Y and an advance red light ARS will take their place, advising him that he has entered a caution block, and thus checking the caution signal Y and advising him also of the condition ahead, it being assumed, of course, that block #3 is occupied.

If the train proceeds under control and for any reason the engineer becomes incapacitated, an automatic application of the brakes will be had at proper braking distance from the home block. It may be noted here that the signals "clear" green signal G, the yellow caution signal Y, and the red danger signal R correspond to the wayside signals, if these are used.

On a caution block the action of the locomotive apparatus will differ in regard to the speed at which the train is travelling at the moment it passes the caution board. There are three different limits of train speed which govern the automatic brake application, namely: high speed, medium speed, and low speed. These will be referred to hereinafter.

Clear block any speed.

Control circuit.—From track rail system

through polarized relay PR, thus closing contacts 17, 16. This establishes circuit from plus of battery VB to SAR, contact 16, armature 17 of PR to minus of battery VB. Energizing of relay SAR closes circuit at 18 of a governor relay GOV, and this is then energized and closes a circuit at 19, which energizes the signal relay S and the time limit relay TL.

The signal relay S sets arm 20 on contact 21 and the green (clear) signal G is lighted, the circuit therethrough being from plus to minus of the battery.

The energizing of time limit relay TL keeps its armature at 23 closed and hence 80 solenoid 30 will be maintained energized, and as this is the solenoid which controls the EAV valve or trigger valve of the Clifford application, the brakes will be held off. An advance red signal relay AR will also 85 be energized, but this will have no effect in lighting the advance red signal ARS because of the circuit being open at 22.

In the above example all of the relays on the vehicle are energized and their contacts 90 are picked up. The governor contacts LSL and HSL are open. LSL closes below low speed limit and HSL closes below high speed limit.

Advance signal block.

Now supposing the vehicle enters block #1, Figs. 4 and 6, which is the second block on the approach side away from the occupied block #3, and in which block #1, as above described, the polarity of the imposed current has been changed for the purpose of getting an advance caution indication, the result will be that the armature 17 of polarized relay PR, because of the change of 100 polarity of the circuit derived from the trackage, will contact with point 15 instead of point 16, and hence the circuit will be closed through the "advance" yellow signal AYS to warn the engineer that he is approaching a caution board, having no effect, however, upon the automatic braking system, because solenoid 30 remains energized.

Under these conditions coil AY will be energized, closing contact at 28 and maintaining energized the slow acting relay SAR, which because of its slow action does not become de-energized while armature 17 of PR is passing from 16 to 15 and hence does not open circuit at 18. This maintains contacts at 18 closed and maintains energized the relay GOV, which maintains the circuits at 19, 24, thus maintaining the relays S and TL energized, the latter maintaining the circuit at 23 so that relay AR and solenoid 115 30 will remain energized. The result of maintaining the relay S energized is that the green "clear" signal G will be maintained by making contact at 20, 21, and this green signal will exist simultaneously with 120 125 130

the "advance" yellow signal AYS. This will enable the engineer to check up on the operativeness of the roadside signals, and will give him an indication of the condition of the signal being approached, which may be around a curve or in like situation where he yet can not observe it. The automatic stop mechanism will not be operated in the above example because the solenoid 30 will be maintained energized.

The maintaining energized of the relay AR will maintain contact arm 25 on point 26, but the circuit to this contact and therefore to lamp AR "advance red" will be broken at 20, 22, hence only the green and advance yellow signals will be displayed.

Signals AYS and ARS indicate the conditions of the signals in advance or those being approached, and Y and G indicate the conditions of the signals last passed. Signal R indicates that a brake application has been effected, as foretold by the signal ARS.

Dead block at high speed.

Now if the vehicle runs into a caution or dead block as #2, i. e., one in which there is no current in the trackway, and calling for a stop, the relay PR will be de-energized and its contact arm 17 will assume neutral position between contacts 15 and 16. Relay SAR will be de-energized, opening circuit at 18, thus de-energizing relay GOV, which will open circuit at 19, de-energizing signal relay S, and causing arm 20 to contact with point 22. De-energizing of the relay GOV will also break the circuit at 24, HSL being open thus de-energizing relay AR and allowing arm 25 to break contact with point 26 and make it at 27, with the result that the red light R will be displayed.

The automatic train stop circuit will be broken at 24 by the de-energizing of the relay GOV and the solenoid coil 30 will be de-energized, and hence, as set forth in the Clifford application, the brakes will be applied for a stop.

Passing a caution or distant indication (a board at 45° for day and a yellow light for night), or in other words, passing from block #1 into block #2 of Fig. 4 at moderate control speed.

Now if the engineer has acted according to the indication given by the advance causation signal AYS, while in block #1, and has slowed down his train, simultaneously, on passing the insulated joints of the distance signal or caution board, the green G and AYS (advance yellow) lights will go out and the yellow light Y and ARS (advance red signal) will take their places. This will be due to the following conditions which will be set up:

All relays except relay AR will be de-energized. LSL (low speed limit) contact of

the speed governor SG will be open and HSL (high speed limit) contact will be closed. Relay AR and solenoid 30 will stay energized for a predetermined time, or until the armature of time limit relay TL, at 23, has travelled a certain distance necessary before opening the circuit. During this predetermined time the path of current flow will be from plus of battery VB through relay AR and through solenoid 30, contact 23 of TL relay, which has not opened yet, and point 29. The current is diverted here to closed contacts at HSL by reason of circuit at 24 being open, through speed governor common wire CW to point 31 to minus of battery.

The result of this condition will be that circuit will be closed at 25, 26, contact will be closed at 20, 22 of signal relay S, and current will go from plus of battery through both ARS (advance red signal) and through yellow light Y to minus of battery. This combination of signals will persist until the TL relay breaks the circuit at 23.

The said combination of signals will tell the engineer while in block #2 that he has passed a distance indication (caution board) because he sees the light Y, and observing of the light ARS, indicates to him that he is approaching a home board or stop indication. He will also get a stop if the train runs beyond the time interval necessary to open the circuit at 23 by the time limit relay. This interval will allow the train to traverse, say $\frac{1}{8}$ of the caution block, well within braking distance from the home board. If the train passes over the $\frac{1}{8}$ distance, then the automatic brake apparatus will operate to stop the train, because the relay TL will break the circuit at 23 and the solenoid 30 will be de-energized. This will de-energize relay AR and arm 25 will then break the circuit at 26, putting out lights Y and ARS, and make the circuit at 27 and lighting the danger signal R.

A train running at an arbitrary low speed.

If an engineer on approaching a home board reduces his speed down to an arbitrarily prescribed low limit, say, of 4 miles an hour, he can pass the home board into the occupied block, in order, for instance, to assist another train which may be stalled for lack of power, or to search for the reason that caused the wayside signal to display a stop indication.

It will be obvious that this eliminates automatic braking and he can proceed as long as this prescribed slow speed is maintained, or until the condition or obstruction is removed.

The conditions obtaining under slow speed when the engineer is approaching the occupied block are as follows: The contact arm 17 of relay PR will be in neutral posi-

tion, owing to absence of current in the rails of this caution block. The low speed limit contact LSL will be closed by the speed governed means SG. All relays will be deenergized, excepting AR and solenoid 30. The signal circuit will therefore be from plus of battery through 20, 22 (relay S being deenergized), through 25, 26 (relay AR being energized), and the current then divides and goes through the advance signal light ARS and through the yellow signal Y to minus of battery. As the speed governed low speed limit contact LSL is closed, the current through the solenoid 30 will be from plus of battery to point 32, through the solenoid to point 33, through LSL, and common wire CW of governor to point 31, and thence to minus of battery, and the brakes will be held off. Breaking of time limit contact at 23 will not affect this circuit.

Should the engineer attempt to accelerate his speed, the contact LSL of the speed governed means SG will open, thus opening the circuit through the solenoid, causing the brakes to be applied automatically, and the train will be stopped, it being understood that the circuit at 24 is already open, due to deenergized relay SAR.

The sensitive relay PR is designed to withstand shock, oscillation and jar, and closes on its contacts at approximately 1.5 millivolts. The track wiring is designed to give, say ten times more voltage than is required for operation.

It will be understood from the above that going at 15 miles an hour, which is arbitrarily fixed as a control speed, if the engineer passes a distant or caution signal into a dead block, he can proceed until the time limit relay opens the circuit at 23, after the lapse of the prescribed time, whereupon he will get a red signal and an automatic stop, if he has not already taken action, or if the conditions ahead have remained unchanged. If the conditions ahead clear, then he can proceed, the automatic system having no effect.

Referring to the modified forms of primary relay connections, Fig. 7 shows the relay connected in parallel with both rails. If the connection on one side should go out of service that on the other side will still operate the relay.

In Fig. 8 the drop in potential which is utilized to operate the primary relay is that taking place between the front wheel and axle on one side and the rear wheel and axle on the other side of the vehicle or engine and tender combined.

In Fig. 9 is shown a modified form of relay which will be substantially unaffected by shocks or jars. It includes two swinging arms α , β and associated coils for controlling them, each being in its own connection receiving current because of the drop in po-

tential between its points of contact with the axles, wheels and trackage, and each arm has back and front contacts e , d , the two front contacts e being electrically connected, and the two back contacts d are also electrically connected, the result being that the pair of contacts for one arm is displaced 180° in respect to the other pair of contacts d and e of the left hand pair being respectively at left and right of their armature, while d and e of the other pair being at right and left respectively of their armature. Under one condition of the trackage, electrically considered, both arms will be on their front contacts, and under an absence of this condition they will swing to neutral position, whereas upon change of polarity of the track current both arms will be on their back contacts d . When in the position shown, or if both are on their contacts d , it will be seen that shock or jar which will tend to dislodge one arm from its contact will tend to press the other arm harder upon its contact, and hence the circuit controlled by this relay will be maintained, and this is true under a reversed polarity of the trackage circuit. Another advantage of this relay is that if one connection is broken the other will maintain the desired circuit.

Like in the said application of Clifford, the primary relay is mounted on an engine or engine and tender of any standard type. It is operated by the current in its conductor connected with points on the track system between which a drop in potential takes place. Similarly no insulating of axles, wheels, or other parts of the standard vehicle equipment is necessary, and the tracks of the railway are of the standard type, having no special sections, and giving continuous control. The conducting wire in which the relay is located may be connected with the axle journal boxes whereby the current will be received through the brasses thereof, as stated in an application of even date herewith, though the invention is not limited in this respect.

Where the system is used in connection with a wayside signalling system the primary relay may be such as to be unaffected by the signalling current alone, its operation one way depending upon the current imposed on the trackage additionally to that used for wayside signalling, and its operation to neutral being due to absence of the imposed current and its reversal to a change of polarity of the imposed current.

The primary relay PR is of the Depre D'Arsonval type, its armatures or pointers closing on its contacts on, say, potential above plus or minus 1.5 millivolt. This type of relay is like that made by The Weston Electrical Instrument Company of Newark, N. J., model 30, and disclosed as to its general features in Letters Patent of the

United States of Edward Weston for instance #611,722 Oct. 4, 1898, or 446,489 Feb. 17, 1891.

This is shown in Fig. 10, in which the pointer or swinging contact arm is carried by a spool or coil p^1 , arranged to turn between the pole pieces of a magnet p^2 , when current passes through the coil from the rail or rails, and thus set the arm against its contact.

10 The rail or frame of the vehicle provides a bridge between the terminals of the coil or spool and the current produced by the tendency of the spool to vibrate, when receiving no current from the rail, and when subjected to jar a shock will oppose the vibration of the coil and thus maintain the pointer or swinging arm in neutral position out of engagement with its contacts, thus rendering the relay suitable for controlling apparatus on a locomotive where more or less vibration necessarily takes place.

15 In the drawing the spool is shown as connected directly with its leads, the coil springs ordinarily used between the spool terminals and the leads being omitted for clearness of illustration.

The current imposed on the track may be say 7 amperes.

20 30 The speed governed means SG may be of the general form disclosed in said prior application, wherein a centrifuge operates a contact *cw* to close contacts HSL and LSL, Fig. 5^a.

35 The time limit relay like in said application may have its armature retarded and slideable along a long contact, indicated diagrammatically at 23, Fig. 5.

The result of deenergizing the solenoid 30 40 is that train line air will be released for setting the brakes.

45 Features relating to the primary relay per se and its connection with the track system are claimed in an application filed of even date herewith, Serial Number 610,880, and in application No. 620,286, filed February 20, 1923. Other features are claimed in the application Serial Number 553,429 of June 17, 1922.

50 I claim—

55 1. In combination in train control apparatus a non-inductive primary relay on the vehicle to control the operation of apparatus thereon, said relay being electrically connected conductively with the track system to be affected by the drop in potential between its points of contact with said track system, a roadside signalling system including a track way relay for each block for controlling the operation of the signals, means for energizing the tracks by direct current for signalling, and for imposing additional direct electric potential upon said track system, when the block is occupied and for 60 withholding said imposed current from the

block in rear of the occupied block, for operating the said primary relay and means for preventing said imposed direct electric potential from interfering with the operation of the signal system, substantially as described.

65 2. In combination in train control apparatus a primary relay on the vehicle to control the operation of apparatus thereon, said relay being electrically connected conductively with the track system to be affected by the drop in potential between its points of contact with said track system, a roadside signalling system including a track way relay for each block for controlling the operation of the signals, means for energizing the tracks for signalling, and for imposing additional electric potential upon said track system, when the block is occupied, for operating the said primary relay and means 70 for preventing said imposed electric potential from interfering with the operation of the signal system, said means consisting of a source of current and a circuit for imposing electric potential, to balance the imposed potential first mentioned in respect to its influence upon a part of the signalling system both the imposed and balancing circuits connecting with the trackway rail system at the ends of the block, substantially as described.

75 3. In combination in train control apparatus, a primary relay on the vehicle to control the operation of the apparatus thereon, said relay being electrically connected conductively with one of the trackway rails at separated points to be operated by the drop in potential between said points, a roadside signalling apparatus including in each block a track relay for controlling the signals, means for energizing the rails for signalling, and for imposing additional electrical potential on the rail with which the primary relay is connected, when the block is occupied, and means for impressing upon the other rail, at the same time, electrical potential substantially equal to that imposed on the rail first mentioned to prevent interference with the operation of the trackway relay and the signals belonging to said block.

80 4. In combination in train control apparatus, a direct current primary relay on the vehicle to control the operation of apparatus thereon, said primary relay being arranged conductively to measure the drop in electrical potential between separated points along the tracks, track relays for controlling the operation of the signals, means at each block for impressing additional direct electrical potential upon the blocks for operating the said primary relay upon the entrance of the vehicle into the blocks, and means whereby the direct electrical potential will be balanced on the two sides of said track relay to 85

prevent interference with its normal operation in controlling the signals.

5. In combination in train control apparatus, a direct current primary relay on the vehicle electrically and conductively connected to separated points on one of the rails to control the operation of apparatus thereon, a road side signalling apparatus including a track relay for each block for controlling the operation of the signals, said relay being connected across the trackway rails, means at each block for energizing the rails with direct current and for imposing additional direct electric potential upon the rail with which the primary relay is connected for controlling the same, and means for simultaneously imposing upon the other rail a direct current of potential substantially equal to the additional potential first mentioned so as to balance the imposed potentials at both sides of the track relay so that the normal operation of the said relay will not be interfered with, both the imposed and the balancing circuits being connected at the ends of the trackway rail system of the block, substantially as described.

6. In combination in train control apparatus, a direct current primary relay on the vehicle electrically and conductively connected to separated points on one of the rails to control the operation of apparatus thereon, a road side signalling apparatus including a track relay for each block for controlling the operation of the signals, said relay being connected across the trackway rails, means at each block for energizing the rails with direct current and for imposing additional direct electric potential upon the rail with which the primary relay is connected for controlling the same, and means for simultaneously imposing upon the other rail a current of potential substantially equal to the additional potential first mentioned so as to balance the imposed potential at both sides of the track relay so that the normal operation of the said relay will not be interfered with, said imposed circuits connecting with the ends of the rails of the blocks, the additional electric currents imposed upon the two rails being derived from independent sources.

7. In combination in train control apparatus, a primary relay on the vehicle sensitive to variations in the electrical condition of the track rails of the block, a relay in each block for controlling the signals along the roadside, a circuit for each rail of the track in each block, contacts controlled by the track relays for closing said circuits when the relay of the block belonging thereto is shunted by the presence of the train, said circuits being also closed at the front contacts of the relay of the unoccupied block next ahead, and means for imposing current

upon said circuits when closed and upon the said primary relay, the corresponding circuit of the next following block remaining open so long as the block ahead remains occupied and its relay deenergized to thereby operate the signals.

8. In combination in a train control system a primary relay on the vehicle to control the apparatus on said vehicle, and deriving its current conductively from the track system, a roadside signalling apparatus with a track relay in each block, means for energizing the rails of the block with which said relay is connected, and circuit connections for impressing additional current for controlling the primary relay, said circuit connections being closed by the dropping of track relay contacts of the occupied block, consequent upon the presence of a vehicle in the block and the shunting of the track relay belonging thereto, said circuit connection being closed by the front contacts of the energized track relay of the unoccupied block ahead, the corresponding circuit connections of the block next following the occupied block being open so long as the condition of the occupied block is maintained, whereby a vehicle entering said next following block will receive no additionally imposed current through its primary relay, substantially as described.

9. In combination in a train control system a primary relay on the vehicle to control apparatus on the said vehicle, said primary relay being electrically and conductively connected with the track system, a signal controlling relay in each block having in addition to its signal contacts other contacts controlling circuit connections to the track system, for imposing current thereupon for controlling the operation of the primary relay on the vehicle, said circuit connections being controlled also by the signalling relay of the next block ahead in the current of traffic, and each of said relays being deenergized by the presence of a vehicle in its block, to close said circuit connections, a pole changing relay in each block, the circuit of which is controlled by the signalling relay of said next block ahead, due to the presence or absence of a vehicle therein, and each of said pole changing relays controlling the polarity of the circuit of the next block in its rear, in the current of traffic, said primary relay being polarized so that the reversal of the polarity of its controlling circuit due to the deenergizing of the pole changing relay of the "stop" block will cause said polarized primary relay to indicate an advance caution signal, substantially as described.

10. In combination in train control apparatus, a primary polarized relay on the vehicle for controlling apparatus thereon, said

- relay being in electrical and conductive connection with the track system, means for imposing current upon the trackage of a block as a consequence of the vehicle entering said block to control the primary relay, for a "proceed" indication or condition of the apparatus on the vehicle and for simultaneously opening the circuit of the next following block in the direction of the traffic to control 10 the primary relay of the vehicle of that block for producing a prescribed indication or condition, and means for reversing the polarity of the circuit in the block in rear of the caution block for operating the primary relay 15 of the vehicle entering said block to produce an advance caution indication, substantially as described.

11. In combination in train control apparatus, a primary polarized relay on the vehicle for controlling apparatus thereon, said relay being in electrical and conductive connection with the track system, means for imposing current upon the track system of a block as a consequence of the vehicle entering said block to control the primary relay, for a "proceed" indication or condition of the apparatus on the vehicle and for simultaneously opening the circuit of the next following block in the direction of the traffic to control 20 the primary relay of the vehicle of that block for producing a prescribed indication or condition, speed controlled means for determining whether said indication or condition will be for caution or 25 stop, and means for reversing the polarity of the circuit in the block in rear of the caution block for operating the primary relay of the vehicle entering said block to produce an advance caution indication, substantially 30 as described.

12. In combination in train control apparatus, a primary polarized relay controlled as to its position by the presence, absence, or reversal of the current of the block, signal 45 means on the vehicle having an indication for advance caution, caution, clear and danger conditions, to distinguish each condition from the others, means for energizing a block as a consequence of its occupancy under proceed conditions, and for simultaneously deenergizing the caution block and 50 energizing the advance caution block in the reverse direction, said polarized relay controlling the said signals, the advance caution signal being displayed when the primary relay changes under the reversal of polarity of the current from its normal direction, sub- 55

danger conditions, to distinguish each condition from the others, means for energizing a block as a consequence of its occupancy under proceed conditions, and for simultaneously deenergizing the caution block and 65 energizing the advance caution block in the reverse direction, said polarized relay controlling the said signals, the advance caution signal being displayed when the primary relay changes under the reversal of polarity of the current from its normal direction, the 70 clear signal persisting simultaneously with the advance caution signal.

14. In combination in a train control system, a primary polarized relay on the vehicle, controlled by the presence and absence 75 of prescribed current in the block, and by the changes in polarity of said current, means on the vehicle controlled by said relay, and 80 means affected by the vehicle in an "occupied" block, for establishing said prescribed current in said block, for absenting said prescribed current from the adjacent caution block, and for reversing the polarity 85 of the said prescribed current in the approach block adjacent the caution block i. e., 90 in the block on the opposite side of the caution block from the "occupied" block.

15. In combination in a train control system, a primary polarized relay on the vehicle, controlled by the presence and absence 95 of prescribed current in the block, and by the changes in polarity of said current, means on the vehicle controlled by said primary relay, and means affected by the vehicle in an "occupied" block, for establishing 100 said prescribed current in said block, for absenting said prescribed current from the adjacent caution block, and for reversing the polarity 105 of the said prescribed current in the approach block adjacent the caution block, i. e., in the block on the opposite side of the caution block from the "occupied" block, and brake apparatus controlled by 110 said primary relay to withhold a brake application under a clear block signal or under an advance caution signal, and to make a brake application under a danger signal and a deferred application under a caution signal.

16. In combination in a train control system, a primary polarized relay having an arm to make either a normal or a reverse direction circuit and including a rotary armature carrying said arm and in a conductor in continuous contact with the track system, the terminals of said conductor being 115

block, and for reversing the polarity of said prescribed current in the approach block, i. e., the block on the opposite side of the caution block from the occupied block, substantially as described.

17. In combination in a train control system, a primary polarized relay on the vehicle, controlled by the presence and absence of prescribed current in the block, and by the changes in polarity of said current, means on the vehicle controlled by said primary relay, and means affected by the vehicle in an "occupied" block, for establishing said prescribed current in said block, for absenting said prescribed current from the adjacent caution block, and for reversing the polarity of the said prescribed current in the approach block adjacent the caution block, i. e., in the block on the opposite side 70 of the caution block from the "occupied" block, and signals on the vehicle for indicating the condition of the blocks, substantially as described.

18. In combination in a train control system, a primary relay on the vehicle in a conductor having its terminals in continuous contact with the traffic rail system and receiving current conductively due to the drop in potential between said terminals, means affected by the vehicle for imposing direct current upon the rail system of an occupied block for absenting said current from the rail system of the caution block and for reversing the polarity of said direct current 80 in the rails of the advance caution block, i. e., the block on the other side of the caution block from the occupied block, and means on the vehicle controlled by said primary relay, substantially as described.

19. In combination in a train control system, a primary polarized relay on the vehicle, controlled by the presence and absence of prescribed current in the block and by changes in polarity of said current, a slow acting relay controlled by the primary relay, means on the vehicle controlled by said slow acting relay and means affected by the vehicle in an "occupied" block for imposing current of normal polarity in the rail system thereof, for absenting current from the rails of the caution block, and for reversing the polarity of the current in the advance caution block, substantially as described.

20. In combination in a train control system, a primary polarized relay on the vehicle, a circuit in each block to control the primary relay of the vehicle entering said block, each of said circuits being controlled by a pair of relays one of which is in one block and the other in the adjacent block, the circuit of the occupied block being closed by the presence of the vehicle therein, relays in each block for changing the polarity of the controlling circuit for the primary re-

lay of the next following block, in the direction of traffic, each of said latter relays being controlled by the circuit controlling relay of the block in advance in the direction of traffic so that when the controlling 70 circuit of said advance block is closed consequent upon the presence of a vehicle therein, the polarity changing relay of the next following block will be operated to change the polarity of the controlling circuit of the 75 next block in its rear to cause the primary relay of the vehicle in said block to indicate an advance caution condition, substantially as described.

21. In combination in a train control system, a primary polarized relay on the vehicle, a circuit in each block to control the primary relay of the vehicle entering said block, each of said circuits being controlled by a pair of relays one of which is in one block and the other in the adjacent block, the circuit of the occupied block being closed by the presence of the vehicle therein, relays in each block for changing the polarity of the controlling circuit for the primary relay 90 of the next following block, in the direction of traffic, each of said latter relays being controlled by the circuit controlling relay of the block in advance so that when the controlling circuit of said advance block is closed consequent upon the presence of a vehicle therein, the polarity changing relay of the next following block will be operated to change the polarity of the controlling circuit of the 95 next block in its rear to cause the primary relay of the vehicle in said block to indicate an advance caution signal, the closing of the circuit in the occupied block opening the primary relay controlling circuit 100 of the said next following block to secure a 105 prescribed indication or condition of the apparatus on the vehicle entering the last mentioned block, substantially as described.

22. In train control apparatus, a primary relay on the vehicle for controlling apparatus thereon said primary relay being in a conductor having its terminals in continuous electrical connection with the track rails and receiving direct current due to the drop in potential between the points of contact with the rails, a track battery for each block, a relay in each track battery circuit, a circuit in each block in respect to which the primary relays cut in upon the entrance of a vehicle, into the block, said circuits being closed by the shunting of the track relay of the occupied block and the maintained energized condition of the track relay in the block ahead in the direction of traffic, the closing of said circuit at the shunted relay 110 opening the circuit of the next following block, substantially as described.

23. In train control apparatus, a primary relay on the vehicle for controlling apparatus thereon said primary relay being in a 130

- conductor having its terminals in continuous electrical connection with the track rails and receiving direct current due to the drop in potential between the points of contact with the rails, a track battery for each block, a relay in each track battery circuit, a circuit in each block in respect to which the primary relays cut in, upon the entrance of a vehicle into the block, said circuits being closed by the shunting of the track relay of the occupied block, and the maintained energized condition of the track relay in the block ahead in the direction of traffic, the closing of said circuit at the 5 shunted relay opening the circuit of the next following block, each of said relays controlling signals on the roadway, substantially as described.
24. In train control apparatus, a primary relay on the vehicle for controlling apparatus thereon, a track battery for each block, a relay in each track battery circuit, a circuit in each block in respect to which the primary relays cut in, upon the entrance of a vehicle into the block, said circuits being closed by the shunting of the track relay of the occupied block and the maintained energized condition of the track relay in the block ahead in the direction of traffic, the 10 closing of said circuit at the shunted relay opening the circuit of the next following block, a relay in each block for changing the polarity of the controlling circuit of the next block in its rear, each of said pole changing relays being controlled by the relay of the controlling circuit of the block next ahead, substantially as described.
25. In combination in train control apparatus, a three position polarized relay on the vehicle, means for delivering a current thereto of different polarity according to the electrical conditions in the blocks of the railway, signals on the vehicle giving a clear, caution and danger signal according to the 15 setting of said polarized relay when the current is of one polarity, an advance signal on the vehicle controlled by the said relay and displayed when the polarity of said current is changed, said advance signal being distinctive in respect to the other signal indications substantially as described.
26. In train control apparatus, a track divided into blocks with means for reversing the polarity of a circuit in a block when the second block ahead is obstructed, a polarized relay on the vehicle receiving current from the said circuit, an advance signal on the vehicle to give an indication of the condition ahead, signals on the vehicle corresponding to block signals, whether the latter are used or not, said advance signal being displayed as a consequence of the polarized relay receiving a current reversed as to polarity, substantially as described.
27. In train control apparatus, a track di-

vided into blocks with means for reversing the polarity of a circuit in a block when the second block ahead is obstructed, a polarized relay on the vehicle energized from the block circuit, an advance caution signal on the vehicle to give an indication of the conditions ahead, other signals on the vehicle for clear, caution, and danger, all of said signals being controlled by the primary relay, said advance caution signal being displayed as a consequence of the polarized relay becoming energized and reversing its position from a reverse polarity block circuit, substantially as described.

28. In train control apparatus, a track divided into blocks with means for reversing the polarity of a circuit in a block when the second block ahead is obstructed, a polarized relay on the vehicle energized from the block circuit, an advance caution signal on the vehicle to give an indication of the conditions ahead, other signals on the vehicle for clear, caution, and danger, all of said signals being controlled by the primary relay, said advance caution signal being displayed as a consequence of the polarized relay becoming energized and reversing its position from a reverse polarity block circuit, and brake applying means controlled by the primary relay to hold the brakes off when said relay is energized and to apply the brakes when said relay is deenergized.

29. In train control apparatus, a track divided into blocks with means for reversing the polarity of a circuit in a block when the second block ahead is obstructed, a polarized relay on the vehicle receiving energy from the said circuit, an advance signal on the vehicle to give an indication of the condition ahead, signals on the vehicle corresponding to block signals, whether the latter are used or not, said advance signal being displayed as a consequence of the polarized relay receiving a current reversed as to polarity, and means for displaying one of the said other signals simultaneously with the advance signal, substantially as described.

30. In combination in train control apparatus, a railway divided into blocks with means for changing the polarity of a circuit in a block when the second block ahead is obstructed, a primary polarized relay on the vehicle receiving energy from said circuit, an advance caution signal on the vehicle displayed as a consequence of the setting of the said polarized relay by the change in the polarity of the trackway circuit, and means controlled by said primary relay for displaying a "clear" signal simultaneously with the advance caution signal, and means controlled by said primary relay for maintaining the brakes off while said advance signal is displayed, substantially as described.

31. In combination in train control appa-

5 ratus, speed governed means on the vehicle, a contact controlled thereby to be closed at a moderate control speed, a caution signal and an advance danger signal on the vehicle, said primary relay being controlled by the electrical condition of a circuit in the caution block, which operates to set said relay for displaying said signals simultaneously and when said moderate speed governed 10 contact is closed, substantially as described.

15 32. In combination in train control apparatus, speed governed means on the vehicle, a contact controlled thereby to be closed at a moderate control speed, a caution signal and an advance danger signal on the vehicle, said primary relay being controlled by the electrical condition of a circuit in the caution block, which operates to set said relay for displaying said signals simultaneously 20 and when said moderate speed governed contact is closed, a time limit relay, electromagnetic means for controlling the brakes, a danger signal, the contact of the said time limit relay when open causing the electromagnetic means to set the brakes, relay means controlling the said caution, advance 25 danger, and danger signals and in turn controlled by the time limit relay so that when the latter opens the caution and advance 30 danger signals will go out and the danger signal will be set, substantially as described.

35 33. In combination, a primary relay on the vehicle having a contact arm which is moved to neutral position by the electrical condition of a caution block, a caution and an advance danger signal on the locomotive, a solenoid for controlling automatic brake applying means and keeping the same off when energized, speed governed means 40 which makes a contact at a prescribed low speed, and electrical means which when said contact is closed displays the said caution and advance danger signals and energizes the solenoid, substantially as described.

45 34. In combination in automatic train control, means for imposing electric potential on the track system in each occupied block and for removing said electric potential in a caution block and for changing the 50 polarity of said electric potential of the block on the approach side of the said caution block, signals on the locomotive, a primary relay on the locomotive to be set in different conditions by the electrical condition 55 of the track system of the blocks, an advance caution signal on the vehicle displayed when the vehicle enters the block on the approach side of the caution block, due to the setting of the primary relay under 60 the changed polarity of the current supplied thereto, a clear signal also on the vehicle displayed under the above conditions, and a danger signal displayed by the further setting of the primary relay when the vehicle 65 enters the caution block, the said primary

70 mary relay then putting the advance caution and the clear signals out, substantially as described.

75 35. In combination in a train control mechanism, signals on the vehicle corresponding to block signals, and other signals, one being an advance caution signal and the other an advance danger signal, and a primary relay on the vehicle controlling 80 said signals, to make those corresponding to block signals harmonize therewith and to simultaneously display with the clear block signal the advance caution signal, and to display with the caution block signal the advance danger signal, and to display the danger signal alone, said vehicle signals being employed with or without wayside signalling means, substantially as described.

85 36. In combination, a three position polarized relay on the vehicle, a slow acting relay the circuit of which is controlled by the primary relay, an auxiliary relay in circuit with one of the contacts of the polarized relay and controlling a circuit maker for the slow acting relay, a governor relay, a circuit breaker therefor controlled by the slow acting relay, a signal relay and a time limit relay, the circuit of which is controlled by the governor relay, signals, the circuits of which are controlled by the signal relay, an 90 advance signal relay controlling the circuit to certain of said signals jointly with the signal relay, an advance danger signal also controlled by the signal and advance signal relay, the circuit of advance danger signal 95 relay being controlled by the time limit relay, a speed governor having low speed limit and high speed limit contacts, a common wire for said contacts on one side thereof, circuit controllers, one for diverting current 100 through the low speed limit contact and controlled by the time limit relay, and the other for diverting current through the high speed limit contact and controlled by the governor 105 relay, but for the time prescribed by the time limit relay through its circuit controller, a solenoid which when energized holds the brakes off, said solenoid being de-energized when the polarized relay is in neutral condition or when the time limit relay 110 opens the circuit of the high limit contact of the governor, and an advance caution signal in circuit with the pole of the polarized relay which is in circuit when the polarity is reversed, substantially as described. 115

120 37. In combination, in train control apparatus, an advance signal in the cab displaying the character of signal belonging to the block being approached, the cab signal belonging to the block being traversed persisting with said advance signal throughout that block, means for operating said signals electrically from the electrical condition of the block being traversed for a continuous indication. 125

38. In combination in train control apparatus, an advance signal in the cab displaying the character of signal belonging to the block being approached, the cab signal belonging to the block being traversed persisting with said advance signal throughout that block, means for operating said signals electrically from the electrical condition of the block being traversed for a continuous indication, and regular block signals on the wayside or in the cab, the clear and caution of which are displayed simultaneously with the advance signals, caution and danger respectively.
39. In train control apparatus, signals on the vehicle for clear, caution, danger, and advance caution, electrical apparatus on the vehicle affected by the presence, absence, or

polarity of electric energy in the block for controlling said signals, means for imposing electric energy on an occupied block to cause the vehicle apparatus to display the said clear signal, for absenting said energy in a caution block and thereby displaying said caution signal; and for reversing the polarity of the electric energy in the advance caution block and thereby displaying the advance caution signal, and electro-magnetic means on the vehicle for holding the brakes off under normal and reverse polarized condition of the block and to cause the setting of the brakes under absence of current from the block, substantially as described.

In testimony whereof, I affix my signature.

PATRICK J. CLIFFORD.
